UNITED STATES PATENT OFFICE.

WILLIAM C. HIERING, OF NEWARK, NEW JERSEY, ASSIGNOR TO J. E. MERGOTT CO., OF NEWARK, NEW JERSEY, A CORPORATION OF DELAWARE.

METAL BOX.

Application filed October 3, 1925. Serial No. 60,198.

This invention relates to receptacles adapted to receive ashes and stumps of cigars, cigarettes and like litter of tobacco débris.

5 It is one of the objects of the present invention to provide an ash receptacle having a single opening and a support in which the receiver is detachably engaged.

10 It is a further feature to provide the support with securing devices attachable to any plane upright surface, whether rigid or yielding.

Another aim is in the provision of a neat appearing article by the use of which danger of setting fire by partly consumed, still burning butts and stumps, or sparks therefrom is avoided, together with the consequent uncleanly appearance of the premises.

15 While such devices are particularly designed for use within automobiles and cars of the better grade, as in accordance with the requirements of the laws of certain States relative to fire hazards; their utilization is of a far wider scope, as within the household or office, where neatness is observed.

These several features of invention are effectually accomplished by the novel and practical construction and arrangement of parts hereinafter described and illustrated 20 in the accompanying drawings, constituting a material portion of this disclosure, and in which:—

Fig. 1, is a perspective view of a preferred embodiment of the invention, showing the application.

Fig. 2, is a side elevational view of the same.

Fig. 3, is a similar side view of the container in detail, parts being broken away to 40 show the construction.

Fig. 4, is a longitudinal sectional view taken on line 4—4 of Fig. 1.

Fig. 5, is a rear elevational view of the container holder.

45 Fig. 6, is a rear elevational view of the same, one of the attaching elements being removed.

Fig. 7, is a transverse sectional view taken on line 7—7 of Fig. 5.

50 Fig. 8, is a perspective view of the device, looking from the rear and showing a modification in attaching means.

Referring more in detail to the drawings, Figures 1 and 2 show the device as attached 55 to an ordinary wind shield, designated by

the character X, or any other solid upright surface whatever, by means of suckers, generally indicated by the numeral 10.

These suckers are preferably used in pairs, one below the other and are composed of rubber, soft leather or other like pliable, elastic, air-impermeable material molded to produce a circular body having a concave face 11 and convex rear surface 12, its thin edge yielding under pressure as it is forced against a plane surface, causing the face to flatten as shown in Fig. 2.

A neck 13 integrally connects a button head 14, either round or slightly elliptical, having a curved edge extending beyond the neck.

A holder or support is composed of a thin metallic plate 15, an oblong rectangle in profile, having cut out openings 16 near its ends, the sides and upper edges of the openings being sheared and bent to produce lugs 17 suited to receive the sucker buttons 14, permitting the necks 13 to extend outwardly between the in-turned edges of the lugs and thus firmly support the suckers in position for attachment.

The lower edge of the support 15 is bent at a right angle outwardly presenting a ledge 18 having a downwardly curved lip 19 at its extremity and the side edges of the ledge are bent up to form guides 20.

In a similar manner the upper end of the plate 15 is bent forwardly constituting a cover 21 having an opening 22 and provided with down reaching guides 23 at its sides.

A box-like container 24 is composed of a single piece of sheet metal bent to produce four upright walls and a bottom, the container being entirely open at the top and of such dimensions as to agree with the support plate 15 and enter snugly between the ledge 18 and cover 21 of the holder.

90 A protuberance 25 forced outwardly from the bottom wall of the container is adapted to engage in a corresponding opening 26 in the ledge 18 centrally near its front, and upon placing the container on the ledge, as indicated in Fig. 2, the container can be swung backward between the guides 23, the ledge 18 and cover 21 being sufficiently resilient to permit such action.

100 In order to secure the container positively to the support, protuberances 27 are formed on the side walls of the container, the same snap engaging in perforations 28 in the 105

guides 23, thereby retaining the parts in assembled position.

In the modification shown in Fig. 8, a support plate 15' is used in the manner described but in place of the suckers, the plate is sheared and bent to produce pairs of loops 30 to receive the straight horizontal portion 31 of the bar pins, one end of the bars being bent reentrantly as at 32, the inreaching elements 34 extending to the center of the plate and then directed outwardly for some distance to constitute pins 35.

It will be understood that this arrangement is adapted to engage with an upholstered or yielding surface on which the sucker devices are not applicable.

Obviously the devices may be placed wherever most convenient and will adhere until forcibly removed; however the container is instantly releasable or replaceable at will, and when in operative position is easily accessible to receive ashes and like refuse.

Although the foregoing is descriptive of the preferred embodiment of the invention, it will be apparent that minor changes may be

made in its construction, without the exercise of invention or conflicting with the scope of the claim hereto appended.

Having thus described my invention, what I claim as new and desire to secure by Letters Patent, is:

An oblong rectangular box composed of sheet metal open at the top, a support plate at the rear, said plate having upper and lower forwardly extending elements to engage the top and bottom of the box, the upper element containing an ovoidal opening leading to the interior of the box and the lower element having an outturned edge and being provided with a depression, a node on the bottom wall of said box to resiliently engage in the mentioned depression, flanges on both of said plate elements to embrace the sides of said box, the flanges on said upper elements having perforations, and corresponding projections on the side walls of said box to engage in the perforations of said flanges.

This specification signed and witnessed this 2nd day of October, 1925.

WILLIAM C. HIERING.
